US00D476574S

(12) **United States Design Patent** (10) Patent No.: **US D476,574 S**
 Beachum et al. (45) Date of Patent: ** Jul. 1, 2003

(54) **BOTTLE**

(75) Inventors: **Chad Beachum**, Allendale, MI (US); **Charles Curtiss**, Long Island City, NY (US); **Nicholas Latorre**, Spring Lake, MI (US); **Stuart M. Leslie**, Larchmont, NY (US)

(73) Assignee: **Gerber Products Company**, Reedsburg, WI (US)

(**) Term: **14 Years**

(21) Appl. No.: **29/151,970**

(22) Filed: **Dec. 12, 2001**

(51) LOC (7) Cl. **09-01**

(52) U.S. Cl. **D9/529**; D9/542

(58) Field of Search D9/529, 530, 541-543, D9/549, 557-558, 300, 521, 574-575; 215/382-384, 396, 398, 400, 371, 375; 220/660, 375; D28/7

Primary Examiner—Ted Shooman

Assistant Examiner—Carol Rademaker

(74) Attorney, Agent, or Firm—Drinker Biddle & Reath LLP

(57) **CLAIM**

The ornamental design of a bottle, as shown and described.

DESCRIPTION

FIG. 1 is a front isometric view as seen from above of a bottle of our new design.

FIG. 2 is a front elevation of the bottle of FIG. 1.

FIG. 3 is a rear elevation of the bottle of FIG. 1.

FIG. 4 is a side elevation of the bottle of FIG. 1, the opposite side elevation being identical but in mirror image.

FIG. 5 is a top plan view of the bottle of FIG. 1.

FIG. 6 is a bottom plan view of the bottle of our new design.

FIG. 7 is a front isometric view as seen from above of a second embodiment of a bottle of our new design.

FIG. 8 is a front elevation of the bottle of FIG. 7.

FIG. 9 is a rear elevation of the bottle of FIG. 7.

FIG. 10 is a side elevation of the bottle of FIG. 7, the opposite side elevation being identical but in mirror image.

FIG. 11 is a top plan view of the bottle of FIG. 7; and,

FIG. 12 is a bottom plan view of the bottle of FIG. 7.
